(57) **CLAIM**

The ornamental design for a manicure glove, as shown, and described.

DESCRIPTION

FIG. 1 is a top view of a manicure glove.

FIG. 2 is a bottom view of the manicure glove shown in FIG. 1.

FIG. 3 is a right side view of the manicure glove shown in FIG. 1.

FIG. 4 is a left side view of the manicure glove shown in FIG. 1; and,

FIG. 5 is a front view of the manicure glove shown in FIG. 1. The broken lines shown in the drawings illustrate the environment of the manicure glove and form no part of the claimed design.

1 Claim, 5 Drawing Sheets

FIG. 1

FIG. 2

FIG. 3

FIG. 4

FIG. 5
